UNITED STATES PATENT OFFICE.

STERLING P. FERGUSSON, OF WASHINGTON, DISTRICT OF COLUMBIA.

KITE-FRAME OR LIKE STRUCTURE.

1,328,143.

Specification of Letters Patent. Patented Jan. 13, 1920.

Application filed October 19, 1917. Serial No. 197,501.

To all whom it may concern:

Be it known that I, STERLING P. FERGUSSON, a citizen of the United States, residing at Washington, in the District of Columbia, have invented a new and useful Improvement in Kite-Frames or like Structures, of which the following is a full, clear, and exact description, reference being had to the accompanying drawings, forming part of this specification, in which:

Figure 1 is a perspective view of one form of kite having my improved connectors applied thereto.

Fig. 2 is a detail plan view of one of the connectors.

Fig. 3 is a sectional view thereof on the line III—III of Fig. 2.

Fig. 4 is a sectional view on the line IV—IV of Fig. 5 of another connector.

Fig. 5 is a plan view of the connector shown in Fig. 4.

Fig. 6 is a sectional view on the line VI—VI of Fig. 7 of another form of connector.

Fig. 7 is a similar view on the line VII—VII of Fig. 6.

Fig. 8 is a sectional view on the line VIII—VIII of Fig. 9 of another connector.

Fig. 9 is a similar view on the line IX—IX of Fig. 8.

Fig. 10 is a side elevation partially in section of still another connector, and

Fig. 11 is a sectional view on the line XI—XI of Fig. 10.

This invention relates to an improvement in frames for kites and like structures, and is designed to provide frames which are cheap of construction, readily assembled, and which are so arranged that any of the brace members can be readily replaced.

The precise nature of my invention will be best understood by reference to the accompanying drawings, which will now be described, it being premised, however, that various changes may be made in the details of construction and the general arrangement of the parts, without departing from the spirit and scope of my invention, as defined in the appended claims.

Referring to the accompanying drawings, the reference character 2 designates the lift planes of the kite, 3 the vertical directive planes and 4 the angular directive plane. These planes are formed of fabric as usual, and are supported by the frame work of the structure. This frame work comprises the

longitudinal brace members 5 of oval cross section, the vertical struts or brace members 6 and the lateral brace members 7 which are also of oval cross section. These various 60 brace members are secured to each other by means of the various forms of connectors shown in detail in Figs. 2 to 11, inclusive. The connectors A which are placed at the eight corners of the structure and shown in 65 Figs. 10 and 11 are provided with socket members 8, 9 and 10. The socket members 8 are arranged to receive the ends of the oval longitudinal brace members 5, while the socket members 9 receive the ends of the 70 oval lateral brace members 7. The greatest diameters of the socket members 8 lie in vertical planes and extend in the direction of the wind, while the greatest diameters of the socket members 9 lie in horizontal planes 75 and extend in the direction of the wind so that these brace members will resist the greatest strains, and present the smallest surface to the wind. One end of each of these sockets is closed to form abutments for 80 the brace members, the sockets extend at right angles to each other and in different planes, so that the ends of the brace members 5 and 7 overlap each other, as clearly shown in the drawings. The sockets 10 are 85 arranged to receive the ends of the vertical brace members 6 at the corners of the structure, and extend laterally from the point where the sockets 8 and 9 cross each other.

B indicates the intermediate connectors 90 for connecting the vertical, longitudinal and lateral braces to each other and are similar to the connectors A. The sockets 9^a in these connectors are provided with through openings for the lateral members 7, while the sockets 8 are closed to form abutments for the ends of the longitudinal members 5. The sockets 10^a are, however, the same as the socket 10 in the connector A, as clearly shown in Figs. 8 and 9. These connectors 100 B are used intermediate the connectors A at all points on the end lateral members, with the exception of the two connectors D on the lower lateral brace 7 at the front of the structure. These connectors are clearly illustrated in detail in Figs. 6 and 7, and are similar to the connectors A and B, with the exception that the sockets 8^b and 9^b are provided with through openings for the longitudinal and lateral braces; the sockets 10^b 110 for the vertical braces being the same.

The lower central longitudinal braces 5

extend through these connectors D to form a bowsprit 12 to which the kite bridle or flying cords 13 are connected.

All of the connectors for connecting two longitudinal members and two lateral members to each other are the same as those shown in Figs. 6 and 7.

The connectors E for connecting the ends of the intermediate lateral brace members 7 to the end longitudinal members 5 and the vertical struts 6 are similar to the connectors A, with the exception that the sockets for the longitudinal members 5 are provided with through openings for said members.

15 The angular directive plane 4 is connected to short longitudinal brace members 14 secured in socket members F and short angular braces 15 secured to these connectors F and C. This plane is shaped about the 20 braces 15 to form the vortex thereof.

The bracket F, as shown in Figs. 2 and 3, is provided with two wing members for the reception of the brace 15, a socket 14^a for the brace 14 and a socket 16^a for a short vertical brace 16 extending upwardly from a T 25 17. This T 17 is connected to a short longitudinal brace member 18. The connectors C, shown in detail in Figs. 4 and 5, are provided with a through socket 10^c for the vertical braces or struts 6, and transverse sockets 9^c for a lateral intermediate brace member 7^a. These connectors are also provided with sockets 8^c for the ends of the short longitudinal braces 18. The sockets 9^c of the 35 intermediate connectors C are provided with through openings for the lateral brace member 7^a, while in the end connectors C one end of each of these sockets 9^c is closed to form an abutment for the brace member 7^a.

40 These connectors C are also provided with wings 19 for the reception of the other end of the brace members 15.

Each of the various connectors is provided with lugs 20 having openings 21 there- 45 through which are arranged to receive the ends of tension members 22, which tension members extend diagonally from one connector to another for holding the frame together.

50 If it is desired to replace any of the various brace members, it is only necessary to release some of the tension members 22, remove the particular brace and replace it with a similar brace, after which the diagonal tension members are again secured in place to hold the structure together.

The advantages of my invention result from the provision of a kite or similar frame having connectors for the reception of brace members provided with abutments for the ends of the brace members, together with means for readily holding the connectors in position with relation to the brace members by means of diagonal tension members, so 65 that any of the brace members can readily

be replaced without the usual lashing of one brace member to another brace member. Also in the provision of connectors in which the sockets for the lateral and longitudinal brace members for the different planes are 70 in different horizontal planes, so that said brace members are adapted to extend from one end of the structure to the other end, or from one side of the structure to the other side of the structure. 75

I claim:

1. A kite or like structure, having a frame built up of a plurality of longitudinal members extending from end to end of the structure, a plurality of transverse members extending from side to side of the structure, connectors at the crossing points of the longitudinal and transverse members, the intermediate connectors having through openings for said members while the end connectors are provided with sockets having end closures to form abutments for the members, vertical strut members, sockets in said connectors for the vertical members, and diagonally disposed tension members connected to adjacent connectors, substantially as described. 90

2. A kite or like frame having a plurality of longitudinally extending members in different horizontal planes, and extending from end to end of the structure, a plurality of transverse members in different horizontal planes extending from side to side of the structure, the transverse members and the longitudinal members being in different 100 horizontal planes, connectors for said members at the crossing points thereof, the intermediate connectors having through openings for the members while the end connectors are provided with closed sockets at one end to form abutments for said members, a vertical strut member extending from the crossing point of one of the horizontal and longitudinal members in one plane to an adjacent crossing point of horizontal and vertical members, sockets in said connectors for said vertical members, and diagonally disposed tension members secured to adjacent connectors, substantially as described. 110

3. A kite or like structure, comprising a plurality of lifting planes in different horizontal planes, directive planes between the lifting planes, a supporting frame for said planes, said supporting frame having a plurality of longitudinal members and a plurality of lateral members extending at right angles thereto for each of the lifting planes, a plurality of vertical strut members for retaining the lifting planes in position relative to each other and for supporting the 125 directive planes, a connector at the junctions of each of the brace members, said connectors having sockets for the reception of the brace members, the sockets for the longitudinal members and the lateral members of 130

the connectors for each of the planes being in different horizontal planes, and diagonally disposed tension members secured to the connectors for holding the parts in position; substantially as described.

4. A kite or like structure having a plurality of upper and a plurality of lower longitudinal extending brace members, a plurality of upper and a plurality of lower 10 transverse brace members, the upper transverse brace members and the upper longitudinal brace members being in different horizontal planes, while the lower transverse brace members are in different horizontal 15 planes from the lower longitudinal brace members, a vertical strut member extending from the crossing point of each of the

lower longitudinal and transverse brace members to the crossing point formed between the upper transverse and longitudinal 20 brace members, a metallic connecting member at each of said crossing points, the intermediate connectors having through openings for the longitudinal and transverse brace members and closed openings for the 25 vertical strut members, the end connectors having closed sockets for the reception of the longitudinal brace members, the transverse members and the vertical strut members, and diagonal tension members connect- 30 ing adjacent connectors.

In testimony whereof I have hereunto set my hand.

STERLING P. FERGUSSON.
